UNITED STATES PATENT OFFICE.

GERALD W. HART, OF WEST HARTFORD, CONNECTICUT, ASSIGNOR TO THE HART MANUFACTURING COMPANY, OF HARTFORD, CONNECTICUT, A CORPORATION OF NEW JERSEY.

COMBINED LIGHTING AND IGNITION SWITCH.

1,182,088.

Specification of Letters Patent.

Patented May 9, 1916.

Application filed June 17, 1915. Serial No. 34,752.

To all whom it may concern:

Be it known that I, GERALD W. HART, a citizen of the United States, residing at West Hartford, Connecticut, have invented 5 a certain new and useful Improvement in Combined Lighting and Ignition Switches, of which the following is a full, clear, and exact description.

My invention relates to combined light- 10 ing and ignition switches for automobiles and the like, and has for its object to produce a simple and compact switch in which two independent switch arms rotate about a common axis.

15 It further has for its object to produce such a switch in which a single key-actuated bolt locks both of said switch arms simultaneously.

20 The following is a description of an embodiment of my invention, reference being had to the accompanying drawings, in which—

25 Figure 1 shows a plan view of the switch. Fig. 2 shows side elevation. Fig. 3 shows a bottom view. Fig. 4 shows a plan view with the casing and operating levers removed. Fig. 5 shows a plan view with the casing, upper switch arm and levers removed. Fig. 6 shows a section of the 30 switch. Fig. 7 shows a detail of one of the switch arms with its lever. Fig. 8 is a side elevation of the parts shown in Fig. 7 looking in the direction of the arrow, portions being in section. Fig. 9 is a de- 35 tail of the other switch arm with its actuating lever. Fig. 10 is a side elevation of the parts shown in Fig. 9 looking in the direction of the arrow, portions being in section. Fig. 11 is a diagram of circuit con- 40 nections.

Referring more particularly to the drawings: 1 is a base of insulating material.

2 is a casing or cover secured to the base by screws 3. The top of this casing con- 45 tains indication marks, those on one side being "Off," "S-T," "H-T" and "All," these marks signifying respectively the positions of the actuating member passing over them corresponding to the positions of 50 the switch arm for (1) opening the switch; (2) putting the side and tail lights in circuit; (3) for putting the head and tail lights in circuit; (4) for putting all lights in circuit respectively. The other side of

the casing has the marks "S-B," "Off" 55 and "D-B," corresponding to the positions of the lever for the switch arm controlled thereby, for (1) putting the secondary battery in circuit; (2) opening the switch, and (3) putting the dry batteries in circuit re- 60 spectively.

4 is a key-actuated lock carried by the cover.

5, 5, 5 are three contacts carried by the base for controlling ignition circuits and 65 adapted to be connected and disconnected by a switch arm 6 carried by a plate portion 7 and insulated therefrom.

8—8 are two contacts which coöperate with the switch arm 9 carried by and insulated from the plate 7 for controlling 70 the generator circuit.

10—10, etc., are five contacts for controlling the lighting circuits, same being engaged by the switch arm 11 mounted upon 75 the plate 12 and insulated therefrom. The plate 7 is mounted upon the shaft 13. The plate 12 is mounted upon a hollow shaft 14 which surrounds the shaft 13.

15 is a finger-piece engaging the shaft 13 80 so as to actuate the same. The shaft 13 has a recess 16 as shown in Figs. 9 and 10 with which an internally projecting pin 17 engages.

18 is a finger-piece having an inwardly 85 projecting pin 19 which engages with a recess 20 in the upper end of the hollow shaft 14 for actuating that shaft and the switch arm 11 carried thereby. The finger-pieces 15 and 18 are held upon the shaft by a 90 screw 21. The finger-pieces 15 and 16, when their switch arms are both in "Off" position, are in line with one another, extending radially in diametrically opposite directions as shown in Fig. 1. 95

The contacts 5 and 8 and the next succeeding four contacts 10, are connected respectively with binding posts 5', 8' and 10' on the back of the base 1. The other contact 10 is connected by a conductor 22 with 100 the fourth contact 10, counting clock-wise, as shown in Fig. 3. The third contact 10 is connected with the first contact 5, counting clock-wise, as shown in Fig. 3 by a conductor 23, the two contacts last referred 105 to being the storage battery contacts.

The shaft 13 has an arm 24 extending laterally therefrom and passing through a slot

25 in the hollow shaft 14. This arm has a face concentric with the axis of the shaft by which it is carried and is provided with a notch 25. The plate 12 has a portion concentric with the axis of the shaft 13 which is provided with two notches 26 and 27. 5
28 is the bolt of the lock 4 provided with a nose adapted to enter the notch 25 and a pin 29 adapted to enter the notches 26 and 27. 10 When the notches 25 and 26 are in position to permit the pin 29 and the nose upon the bolt 28 to enter them, all the switch arms are in open position. When the notches 25 and 27 are in line with one another and are 15 in position to permit the pin 29 and the nose of the bolt 28 to enter them, the ignition controlling switch arm is in open position and the light controlling switch arm is in the "S-T" position; *i. e.*, in position for placing the side and tail lights in circuit. 20 If the ignition switch is not in open position, the lock 4 cannot be actuated. If the lighting circuit is in neither the open position nor the "S-T" position, the lock cannot be 25 actuated. The circuit therefore can be locked only when the ignition controlling arm is in open position and the light controlling arm is in either open position or side and tail light ("S-T") position, the two 30 positions of the lighting arm just named being those in which the arm should be placed when the machine is left standing for a considerable period during the day and during the night-time respectively.

35 In order to give the two switch arms the proper throw with a semi-snap action, I provide two spring pawls, consisting of rollers 31-32 carried by springs 33-34 respectively, said two rollers being carried by the 40 screw 35 and acting independently upon the plates 12 and 7 respectively, said plates being provided with cam notches with which the pawls engage. These two plates are provided with slots 37-38 through which protrudes a pin 39 carried by the base, acting as 45 a positive stop for said plates at the end of their extreme throws in either direction.

The arm 6 is made of such length that in 50 its central position it is out of engagement with the two end contacts 5 and when in either of its other positions is in engagement with the central contact 5 and with but one of the other contacts 5. The switch arm 9 has three projections, which when the 55 switch arm is in its central position, are out of engagement with the contacts 8. Two of these projections, however, are in engagement with the two contacts 8 whenever the switch arm 9 is in either of its other positions.

The switch arm 11 has two projections, one of which is a bridge adapted to simultaneously engage three of the contacts 10. The other projection is separated therefrom 60 so that when it is in engagement with a con-

tact 10, the contact 10 next adjacent thereto is not engaged by the switch arm 11. This enables the desired selection of lighting circuits to be made.

The circuits are shown in Fig. 11. To the lower-most contact 5 is connected a dry battery 40. The next contact 5 is connected to spark coil 41 and to the upper contact 5 is connected a storage battery 42. To the lower contact 8 is connected a generator 43 and the upper contact 8 is connected by a conductor 44 to the upper contact 5. To the first contact 10, counting clock-wise, in Fig. 11, are connected side lights 45. The next contact 10 is connected to tail light 46. The next contact 10 is connected by a conductor 22 to the storage battery 42. To the next contact 10 is connected the head lights 48. The lower contact 10 is connected by a conductor 23 to the tail light 46.

When the switch arms are in the positions shown in Fig. 4 all switch arms are in open position. When the arms 6 and 9 are moved in clock-wise the storage battery is placed in circuit with the coil and the generator is connected in circuit with the storage battery. When those arms are moved counter-clock-wise from their central positions, the dry batteries are placed in circuit with the spark coil and the generator is placed in circuit with the storage battery. When the switch arm 11 is moved one step clock-wise the side and tail lights are placed in circuit with the battery. When moved another step the head and tail lights are placed in circuit with the storage battery, and when moved a third step all lights are placed in circuit with the storage battery. When the switches are in "Off" position they may both be easily grasped to throw them simultaneously so as 105 to connect the coil and the side and tail lights to the storage battery, that being what is ordinarily desired for automobiles used in the city in the night-time. The free terminals of the batteries, coils and lights above 110 referred to are suitably grounded as shown in Fig. 11.

As will be evident to those skilled in the art, my invention permits of various modifications without departing from the spirit 115 thereof or the scope of the appended claims.

What I claim is:

1. In an electric switch the combination of a base, two switch arms thereon independently revoluble about a common axis, 120 two series of contacts, each arranged concentrically about said axis, two radial handles connected to said switch arms respectively, said handles being in line with one another when both of said switch arms are 125 in open position.

2. In an electric switch the combination of a base, two switch arms thereon independently revoluble about a common axis, two series of contacts, each arranged con- 130

centrically about said axis, two handles connected to said switch arms respectively, and a lock for locking both of said switch arms simultaneously when said switch arms are in open position and means for preventing the action of said lock except when one of said arms is in open position.

3. In an electric switch the combination of a base, two switch arms thereon independently revolute about a common axis, two series of contacts, each arranged concentrically about said axis, two handles connected to said switch arms respectively, said handles being in line with one another when both of said switch arms are in open position, and a lock for locking both of said switch arms simultaneously.

4. In an electric switch the combination of a base, two switch arms thereon independently revolute about a common axis, two series of contacts, each arranged concentrically about said axis, two handles connected to said switch arms respectively, and a lock for locking both of said switch arms simultaneously, and means for preventing the action of said lock except when one of said switch arms is in open position.

5. In an electric switch the combination of a base, two switch arms thereon independently revolute about a common axis, two series of contacts, each arranged concentrically about said axis, two handles connected to said switch arms respectively, said handles being in line with one another when both of said switch arms are in open position, and a lock for locking both of said switch arms simultaneously, and means for preventing the action of said lock when one of said switch arms is out of open position.

40 6. In an electric switch the combination of a base, two switch arms thereon inde-

pendently revolute about a common axis, two series of contacts, each arranged concentrically about said axis, two handles connected to said switch arms respectively, and a lock for locking both of said switch arms simultaneously, and means for preventing the action of said lock except when one of said switch arms is in open position and the other is in one of two positions.

7. In an electric switch the combination of a base, two switch arms thereon independently revolute about a common axis, two series of contacts, each arranged concentrically about said axis, two handles connected to said switch arms respectively, one of said series having five contacts and one of said switch arms having a bridge for connecting any adjacent three of the said five contacts and a tail for engaging another of said five contacts but separated from the bridge by the space occupied by one contact.

8. In an electric switch the combination of a base, two switch arms thereon independently revolute about a common axis, two series of contacts, each arranged concentrically about said axis, two handles connected to said switch arms respectively, and a common stop for limiting the movement of said switch arms in both directions.

9. In an electric switch the combination of a base, two switch arms thereon independently revolute about a common axis, two series of contacts, each arranged concentrically about said axis, two handles connected to said switch arms respectively, said handles being in line with one another when both of said switch arms are in open position, and two spring actuated pawls, one for each of said switch arms, and notches engaged by said pawls.

GERALD W. HART.
